UNITED STATES PATENT OFFICE.

SAMUEL N. POLIS, OF NEW YORK, N. Y.

SHIP.

Application filed September 17, 1917. Serial No. 191,875.

To all whom it may concern:

Be it known that I, SAMUEL N. POLIS, citizen of the United States, and resident of New York city, in the State of New York, 5 have invented certain new and useful Improvements in Ships, of which the following is a specification.

My invention relates to ships and particularly to ships having a special girder construction for strength, and adapted to sail upon the ocean, or canals, lakes and rivers.

My ship is preferably constructed with trusses or girders located within the hull and adapted to carry practically all the 15 bending and shearing stresses to which the hull is subjected. These trusses or girders are surrounded by or have attached to them, plates for the purpose of forming the skin or plating of the ship.

20 My truss construction is adapted to be made of wood, reinforced concrete or other suitable structural material, or steel in the form of cast steel, or rolled and riveted steel.

25 The primary object of my invention is to provide a ship's hull, the framework or skeleton of which is made up of a plurality of longitudinal girders combined with a suitable number of transverse girders; all 30 in rigid relation with one another and adapted to carry the plates or sections which constitute the shell or skin of the ship. With a hull so designed, all of the stresses to which the ship is subjected can be borne by 35 the girders; and principally by the longitudinal girders, with the result that I can obtain a ship's hull of superior strength and yet constituted of a smaller quantity of steel than would ordinarily be required in a ship 40 of the same size and carrying capacity.

45 Preferably I employ two longitudinal girders, located above the bottom of the vessel, and extending from bow portion to stern portion. The transverse girders extend between and connect the longitudinal girders besides running out to the sides of the ship. In any case, the transverse girders from their points of connection with the longitudinal girders to the sides of the ship constitute means for transmitting to the longi-

tudinal girders the effects of the stresses to which a ship is always subjected by the sea, and the effects of the stresses due to the weight of the cargo along the sides of the ship after the same has been loaded.

55

The skin of the ship may be formed of flat sections or sections that are curved in one or more directions or sections that are combinations of flats and curves. This applies to parts of the hull above the water line and below the water line and these forms may be used wherever desired.

60

65 These sections or plates mentioned will be secured to the framework, so as to cover it entirely and will be held rigidly in place, especially as regards the transverse girders referred to.

65

These plates may be of cast or rolled steel, or of wood or concrete, and so may the girders or trusses; and the sections of the skin of the ship may be so shaped as to incorporate parts of the trusses or girders, such as the chord members, if desired.

70

The different parts of the ship where formed of cast or rolled steel may be bolted, riveted, pinned or welded together. The joints may be rendered water tight by usual caulking methods or by welding or by any other suitable method.

75

In the drawings—

80

Fig. 1, shows a plan view of a hull embodying some features of my invention.

Fig. 2, is a side view thereof showing a possible water line.

Fig. 3, shows a longitudinal section thereof.

85

Fig. 4, shows a transverse section of a ship embodying one form of the invention.

Fig. 5, is a sectional view of a ship section showing the attachment of U-channel ribs or frames to the skin plating.

90

Fig. 6, shows a modification thereof for purposes of casting.

95

Fig. 7, shows another modification capable of being cast or rolled.

Fig. 8, shows a transverse section of a modification of my ship.

95

Figs. 9, 10 and 11, show other modifications thereof.

100

Fig. 12, shows a bolted and welded joint

between sections such as shown in Figs. 6 and 7.

Fig. 13, shows a riveted and welded joint between sections such as those shown in Fig. 5.

The same numerals of reference identify the same parts throughout.

Referring first to Figures 1, 2, 3 and 4, I show a ship's hull 15 having deckhouses 10 16; and the skeleton or framework of this hull is indicated as being made up of a plurality of longitudinal trusses or girders 17, and transverse girders or trusses 18. The longitudinal girders 17 are shown as extending 15 between bottom and upper deck from the bow portion to the stern portion of the ship; and the transverse girders 18 are rigid with the longitudinal girders and extend not only between the latter, but out to the sides 20 of the ship. The deck plates of the hull are indicated at 25, and the side and bottom plates at 27.

As illustrated on these first four figures, the longitudinal girders are girders of the 25 truss type, and comprise top chord members 20 and bottom chord members 21; which extend lengthwise of the hull and are connected by vertical web members 22 and diagonal web members 23. See particularly 30 Figure 3. Of course, instead of a truss girder, I may under some conditions use a plate girder with chord members at the top and bottom, as I have in fact indicated in Figure 11. Between the longitudinal girders 35 are diagonal web members 24 and similar web members 24 extend from these longitudinal girders diagonally outward towards the sides and bottom of the hull. See Figure 4.

40 The deck plates 25, and side and bottom plates 27 are similar in construction, and as an example, I show side and bottom plates in cross section in Figures 5, 6 and 7. These plates are provided with re-inforcing ribs 45 or members 26, which may have different cross sectional shapes as these three views illustrate. The deck plates 25 bridge the tops of the girders 17 and extend outward towards the sides of the ship with the ribs 50 26 in transverse position. At the sides of the ship the deck plates are joined to the side plates, which extend downward and are united with bottom plates at the points 29, other bottom plates 27 beginning at the 55 points 30. The ribs 26 of the side and bottom plates or sections likewise extend transversely of the hull and the girders 17. That is to say, the ribs of the deck plates and the side and bottom plates are arranged end to end and extend continuously around the framework of the hull; the ribs of one plate being rigidly connected with the ribs of an adjoining plate by riveting, welding or any other suitable way, and where they cross the 60 girders 17, these ribs are also made rigid

with the top and bottom chord members 20 and 21. See Figure 3. The ends of the diagonal chord members 24, which are shown in Figure 4, as extending downward from the top chord members 20 of each girder, 70 are likewise made rigid above with the chord members 20 and the ribs 26 of the deck plates; and at their lower ends, with the ribs 26 of the side and bottom plates; and the entire skeleton and skin are thus made 75 rigid throughout.

The deck plates are joined to one another by means of the ribs 26 along the edges of these plates; and so are the side and bottom plates. Each rib of any one plate will form 80 with the correspondingly located ribs of the other plates in the same transverse section of the hull a continuous rib extending entirely around the framework of the ship; and the web members 24 may be spaced apart 85 in the direction of the length of the ship in any required manner. For example the web members 24 secured to the girders or trusses 17 at any transverse section of the hull may be located as far from the next set of web 90 members 24 disposed transversely of the hull as the width of one of the side or deck plates measured lengthwise of the hull, or across the ribs 26. When so spaced the members 24 of each set should preferably be in 95 the same transverse plane as the joints between the successive side plates, for instance; and the ends of each of these members 24 will then be fixed to a rib of double size 100 and strength along the side, bottom and deck plates, because two such ribs 26 will there be fastened together. If desired corner plates may be used at the ends of the members 22 and 23; also between the ends of the members 24 and the ribs of the side, deck 105 and bottom plates to make the hull still stronger.

The web members 22 should, of course, be in the same transverse planes as the members 24. 110

It will be seen that the web members 24, which extend downward and towards the sides and bottom of the ship from the girders 17, along with the ribs 26 of the deck, bottom and side plates to which the members 24 are attached, in effect constitute cantilevers. In other words, the members 24 co-operate with these ribs 26 of the deck, bottom and side plates, which ribs also serve as chord members; all these chord members thus constituting means for providing true cantilevers which take care of all stresses along the side of the ship upon which the same is located, no matter whether the stresses are due to the weight of the load acting downward, or the pressure of the water acting upward, or to sea action. 115 120 125

The ribs 26 of the bottom plates and the deck plates between the longitudinal girders also serve as chord members and co-operate 130

with the centrally located diagonal web members 24. These centrally located members 24 and the ribs of the deck plates and bottom plates act as means for connecting 5 the girders 17; and likewise co-operate with the cantilever construction at the sides to form complete transversely extending trusses or girders, mentioned above and indicated in Figure 1 by the numeral 18. Each trans- 10 verse truss or girder and its cantilever ends may be conceived too as including the web member 22 of the truss 17 in the plane of the transverse truss or girder.

The various chord members and web mem- 15 bers of the longitudinal and transverse girders are firmly secured together and thus make up the rigid framework or skeleton of the hull. All of the stresses to which the ship is subjected are borne by these trusses 20 or girders, and the function of the plates or sections 25 and 27 is merely to enclose and protect the cargo, without being required to carry any of the load or resist any of the forces of the sea, excepting pos- 25 sibly the mere local pressure of the water.

Figure 8 shows a modified form of cross section for the hull. The skeleton or framework comprises a pair of longitudinal trusses 17, made as in Figure 3, with centrally located web members 24 that cross each other, instead of being connected to the middle of the bottom as in Figure 4. In this type of vessel the deck is curved towards the sides and the bottom is likewise 25 curved on about the same arc, the deck and bottom intersecting on each side at an acute angle. The deck plates 25 and the bottom plates 27 have ribs 26 as before, which extend transversely of the girders 17 and the 30 ribs 26 of the deck plates are joined at their ends to correspondingly located ribs of the bottom plates. These ribs are, of course, made rigid with the chord members 20 and 21 of the trusses 17 and the ends of the 35 diagonal web members 24 are made fast to the girders or trusses, as will be understood. In this instance, the central web members 24 and the transverse ribs 26 in the same transverse plane as these web members make 40 up the transverse trusses; and the cantilevers on each side of the girders 17 are provided by the aforesaid ribs 26 of the deck and bottom plates, meeting and being fastened together at the intersection of the 45 deck and bottom.

In Figure 9, I show another cross section of hull. This form of hull is constructed in the same manner as that shown in Figure 8, only that the adjacent ends of the deck 50 and side plates are curved so that they do not meet at an acute angle.

In Figure 10, I show another form of hull in cross section, comprising girders 17 made up the same as in Figure 3, and connected by central diagonal web members 24,

the same as in Figures 8 and 9. The deck plates 25 are united to side plates 27 and these plates are united to the bottom plates. The ribs of the correspondingly located deck, side, and bottom plates extend continuously around the hull as before and have their ends joined together in any suitable way. These ribs and the diagonal web members 24 make up the transverse girders or trusses and the ribs 26 of the deck, side and bottom plates extending from the girders outward toward the sides constitute the cantilevers. This type of ship is shown as having a middle or lower deck 58.

In Figure 11, I show longitudinal girders 17^a, which are in fact plate or web girders extending from bottom to deck plates 25 and having upper chord members or flanges 20^a and bottom chord members or flanges 21^a. In this construction I make the cantilever effect more pronounced by designing the transverse girders 18^a so that each comprises a continuous plate or web member 60, extending between the girders 17^a and having a chord member 60^a along its upper edge. 90 From the girders out toward these sides are other webs or plates 60 with chord members 60^a along upper edges, these other plates 60 tapering toward the sides, as shown. The deck plates 25 are secured to the girders 17^a as before but do not bridge them, and are joined to side plates 27. The side plates 27 are united at 29 to bottom plates extending across the bottom of the girders 17 as indicated at 30, the same as in Figures 4 and 10. As already described the ribs of the deck plates 25 will be aligned with and joined to the ribs of correspondingly located side plates and bottom plates, and the ribs of the bottom plates along the lower edges of the plates 60 will be secured to these plates and form the bottom chords. The ribs 26 to the outer sides of the girders 17^a are parts of the transverse girders and of course co-operate with the outer plates 60 and members 60^a to constitute means for providing cantilevers, and the inside plates 60 and members 60^a form those parts of the transverse girders which constitute the means for connecting the girders 17^a.

While I have shown the longitudinal and transverse girders as being plate girders in Figure 11 only, I may use plate girders as transverse and longitudinal girders in any of the other forms of my ship's hull. The kind of girder shown as a longitudinal girder in Figure 3, and as a transverse girder in Figure 4 and comprising chord members along the top and bottom and web members extending transversely between the chord members is generally known in engineering parlance as a truss; and the term girder in engineering means more properly a girder consisting of a web or plate with chord members at the top and bottom, such 130

as shown in Figure 11. In this specification, however, I employ the term girder to cover both forms.

The ends of all the plates 60 of the transverse girders 18^a in Figure 11, at the girders 17^a are, of course, made rigid with the plates of the girders 17^a as by means of vertical angle bars, so that these girders 17^a, serve as points of support for the cantilevers that 10 the ends of the transverse girders provide. In other words, the ends of each middle plate 60 are fastened to the plate girders 17^a along the inner faces of these plate girders, and the ends of each plate 60 which extends from 15 the girders 17^a towards the sides are also fastened to the plate girders. Further the lower edges of the plates 60 between the girders 17^a and of the plates 60 extending from these girders out towards the sides will 20 be fastened to the ribs 26; and the chord members 60^a to the outside of these girders 17^a will be fastened to the ribs 26 at one end and to the girders 17^a at the other end. The chord members 60^a between the girders 17^a 25 will be fastened to the plates 60 between these girders and to the girders 17^a too.

The manner in which two adjacent deck plates, or two adjacent side plates, or two adjacent bottom plates are secured together 30 along the length of the hull, is indicated in Figures 12 and 13. The end ribs of the two plates are simply laid together and joined by bolts and welding, as indicated at 31 and 32 in Figure 12, or by the same welding and 35 rivets as indicated in Figure 13, or by spot welding.

In order to secure the deck side and bottom plates together along the edges which extend across the ribs 26 I preferably employ 40 welding in order to make a perfectly tight and leak proof joint. I may also rivet the plates together along these edges; employing the additional plates which lap over the edges of two adjacent plates for the purpose. 45 Of course welding is preferred, since these plates cannot be riveted together so advantageously along the edges which cross the ribs as they can along the edges which carry these ribs; for to secure two adjacent plates 50 together along the ribs 26 it is only necessary to bring the ribs into contact and then rivet or spot weld them. In some cases, especially when my ship's hull or parts thereof are made of concrete, two or more of these 55 plates can be cast together.

The various parts of the skeleton of the ship may be united by riveting or welding or in some instances by casting two or more of the parts together and assembling them 60 with the other parts as a single unit; and this method of uniting the parts can be adapted both for longitudinal and transverse girders of truss and plate construction.

In cases where I employ girders running longitudinally of the ship, the same

divide the inside of the hull into so many cargo spaces accessible from above; and by the transverse girders, these longitudinal cargo spaces are subdivided into smaller ones. In case where the longitudinal or 70 transverse girders are plate girders and extend from the bottom to the upper deck, they constitute so many bulk heads and divide the inside of the hull into a number of watertight compartments, so that even in case the 75 ship is damaged by torpedo, it can still keep afloat. The compartments localize the damage and even those which are blown open from the side or bottom can still assist in keeping the ship from sinking, because the 80 deck can be made air-tight and a quantity of air will usually be trapped below the deck in any compartment that may be damaged from without; and the buoyant effect of this trapped air will materially assist in keeping 85 the ship afloat.

I, of course, may use as many longitudinal girders either of the truss or plate type as the size of the ship makes desirable. When truss girders are employed the web 90 members may be omitted in some cases; provided the hull and trusses are strengthened in the usual way to compensate for the omission.

Where curves are shown in Figures 1, 2 95 and 3 and 8 to 12 inclusive I do not need to employ curved members but I may use instead a succession of straight members, whether they are plates or web members; these straight parts taking the general direction of the curves and giving the hull and parts thereof the same general configuration as is shown. Such a construction of straight members is in fact illustrated in Figure 4.

In Fig. 4, is shown a center board 33, adapted to be withdrawn into the center board housing or box 34, by any suitable means such for example as the cable or rod 35. A center board may be located wherever 100 desired and various positions are indicated at 36, in Fig. 3. The forms of hull shown in Figures 4, 8, 9 and 10 are well adapted for transversing canals which have side slopes and I wish to call attention to the 105 fact that with the hull shown in Figure 11 I may provide a double bottom by laying plates along the length of the ship on top of the transverse girders 18^a, both between the plate girders 17^a and between these girders 17^a and the sides of the hull.

Besides the upper deck I may use lower decks, one such lower deck being in fact illustrated at 58^a in Figure 10.

If such a lower deck is employed below the 115 upper deck in the form of hull shown in Figure 11 this form of hull with its double sides and double bottom becomes adapted for a ship intended to serve as a tanker for oil or other liquid cargo.

The hatch ways shown at 59 and 59^a in Figure 1 may be in such number as required but preferably there should be one for each separate cargo space made by the arrangement of girders, so that the loading and unloading of the vessel can take place vertically by simply lowering the cargo into the vessel and lifting it out in the same way.

When plate girders are employed for the transverse girders, especially when they extend up at the sides from the bottom to the deck, the various parts of the hull can be advantageously assembled by locating the edges of these girders at the bottom and the sides of the hull between the ribs 26 of the adjacent deck, side and bottom plates and welding these ribs to the girders.

As stated above, the longitudinal and transverse girders divide the inside of the hull into so many compartments or chambers and this construction permits large hatch ways to be provided in the deck so that the cargo can be loaded and unloaded vertically. The size of the compartments can be varied according to the number of girders used; and the shell or skin of the ship will form the bottom of these chambers in the middle of the hull and the bottom or the bottom and sides of such chambers as are placed along the sides of the ship. The longitudinal girders and the transverse girders, particularly the supports provided by the ends of the latter, will hold the plating with sufficient strength to enable the ship to resist safely the stresses.

My form of hull, particularly that shown in Fig. 4, is peculiarly adapted for use with stabilizing devices. A wave hitting the quarters or beams of the hull finds no resistance, no surface against which to exert a force of impact tending to roll the hull, as the sides of the hull are preferably devoid of a vertical surface. The edge 28, and the turtle-back top permit the water to continue on its course over the hull so that the stabilizer in counteracting the rolling action has less work to do. The top and bottom of the hull meet at an acute angle, the vertex of which may be sharp or for convenience somewhat rounded as shown in Fig. 9. Of course, the sides may be flat as shown in Fig. 10, without entirely losing the virtue of this factor, for the shallow draught means sides of small area adapted to reduce the resistance to wave impact, thus reducing the tendency to roll. The top of the hull is of course, water tight, the joints being preferably welded, and the hatches are held down by water tight joints.

While I have described my ship in the form that I prefer to build it, it is obvious that any one or more or all of the features may be utilized alone or in various combinations as may be desired, and the various forms of construction may be varied with-

out departing from the spirit of my invention.

Longitudinal girders of the plate type are especially adapted for large ships.

The use of longitudinal and transverse girders in the above described structural relations saves a great quantity of the steel or other material that is generally required to build ships of the same carrying capacity. This economy of materials is due to the supporting effect of the longitudinal girders on the transverse girders; whereby the latter are made to do duty in several short spans. I thus lessen the shear and bending moment produced by a given weight of cargo, or a given degree of sea action. I can therefore, utilize materials that are smaller in comparison with what a ship of different type will need.

The portions of the transverse girders which are between the longitudinal girders make these longitudinal girders rigid with each other throughout the length of the ship; and the remaining portions of the transverse girders which I have described above as providing cantilevers at the sides of the ship serve as means for transmitting to the longitudinal girders stresses upon portions of the hull, between the longitudinal girders and the sides of the ship; whether those stresses are due to sea action or the weight of the ship's load.

Of course, in practice some stresses necessarily fall upon the deck, side and bottom plating because any bending of the girders due to hogging and sagging necessarily compels a bending of the plating also; and to this extent the plating, too, will act as a girder, even though such plating be relatively thin and light. But in my ship the skeleton is strong enough within the elastic limit of the materials of which it is built to resist all the stresses even should the plating be ruptured or entirely removed.

This statement is made because one may consider the sides of the ship as longitudinal girders although they are not intentionally designed as such. From this point of view the portion of the transverse girders between the sides of the ship and the longitudinal girders 17 can be regarded as simple beams, but in function and effect they are cantilevers, under certain conditions.

It is a common occurrence to have the bilge plating stripped in which case the sides become ineffective as girders. It is also common to have bottom plating loosened or some plating of sides, decks or bottom permanently deformed; which would also seriously affect the longitudinal strength. It is also common for side plating to be stripped by rocks, or smashed in by collision with derelicts or other vessels, and during wars torpedoes are the cause of destroying side

girders and seriously affecting the longitudinal strength.

In all such cases safety is secured if the stresses formerly carried by the side plating were transferred to the interior girders and this would be performed properly by the transverse members extending from the interior girders to the sides of the ship, and connected thereto. These members are in effect transverse girders or portions of transverse girders while the sides of the ship are intact. But the instant that the sides of the vessel are ruptured so as to make them ineffective, the transverse girders immediately function as cantilevers and transfer to the interior longitudinal girders such stresses as were formerly carried by the sides until said sides became ineffective.

Cantilever action may be assumed as occurring either in the original design or in case the plating is destroyed or ruptured in such manner as to make the action of the side girders ineffective for properly resisting longitudinal stresses and the term cantilever is to be understood accordingly.

What I claim is:—

1. In a ship's hull, the combination of a plurality of interior longitudinal girders, means extending transversely of the hull and located between said girders at a plurality of points to connect the same, and means co-operating with the first named means and extending from said girders towards the sides of the ship for constituting, in effect, transverse girders rigid with the longitudinal girders, said transverse girders providing supports for portions of the hull between the longitudinal girders and the sides of the ship, thereby causing stresses upon the hull to be resisted by said longitudinal and transverse girders, the longitudinal and transverse girders dividing the ship into compartments for loading and unloading cargo vertically.

2. In a ship's hull, the combination of a skeleton and a skin to cover same, the skeleton comprising a plurality of interior longitudinal girders, means extending transversely of the hull and located at a plurality of points between said girders to connect the same, means located at each of said points in line with said first named means and extending from said girders towards the sides of the ship for transmitting to said girders stresses upon portions of the hull between said girders and said sides, said means between the girders and said means extending from said girders towards said sides constituting at each of said points a continuous transverse girder rigid with the longitudinal girders, said transverse girders being connected to said skin (adjacent the sides of the ship) and being designed to transmit to the longitudinal girders substantially all the stresses to which said portions

may be subjected, whereby substantially all stresses upon the hull may be borne by said skeleton.

3. In a ship's hull, the combination of a plurality of interior longitudinal girders, means extending transversely of the hull and located between said girders at a plurality of points to connect the same, and means at said points in line with the first named means and extending from said girders towards the sides of the ship for transmitting to said girders stresses upon portions of the hull between said sides and said girders, said means between said girders and said means extending towards said sides constituting at each of said points a continuous transverse girder rigid with the longitudinal girders, said transverse girders providing cantilevers for said portions designed to transmit to the longitudinal girders substantially all stresses to which said portions may be subjected, whereby substantially all stresses upon the hull may be borne by said longitudinal and transverse girders.

4. In a ship's hull, the combination of a skeleton and a skin to cover same, the skeleton comprising a plurality of interior longitudinal girders, means extending transversely of the hull and located at a plurality of points between said girders to connect the same, means located at each of said points in line with said first named means and extending from said girders towards the sides of the ship for transmitting to said girders stresses upon portions of the hull between said girders and said sides, said means between the girders and said means extending from said girders towards said sides constituting at each of said points a continuous transverse girder rigid with the longitudinal girders, said transverse girders providing cantilevers for said portions, said cantilevers being connected to said skin adjacent the sides of the ship and being designed to transmit to the longitudinal girders substantially all the stresses to which said portions may be subjected, whereby substantially all stresses upon the hull may be borne by said skeleton.

5. In a ship's hull, the combination of a skeleton and a skin to cover same, the skeleton comprising a plurality of interior longitudinal girders, means extending transversely of the hull and located at a plurality of points between said girders to connect the same, means located at each of said points in line with said first named means and extending from said girders towards the sides of the ship for constituting at each of said points with said first named means a continuous transverse girder rigid with the longitudinal girders, said transverse girders being connected to said skin adjacent the sides of the ship and providing supports for portions of the hull between

said longitudinal girders and said sides, longitudinal girders, means extending transversely of the hull and located at a plurality 25 of points between said girders to connect the same, means located at each of said

5 points in line with said first named means and extending from said girders towards the sides of the ship for constituting at 30 each of said points with said first-named means a continuous transverse girder rigid with the longitudinal girders, said transverse girders providing supports for portions of the hull between the longitudinal 35 girders and the sides of the ship and being connected to said skin adjacent the sides of the ship, whereby all stresses upon the hull may be resisted.

6. In a ship's hull, the combination of a plurality of interior longitudinal girders, means extending transversely of the hull and located at a plurality of points to connect the same, and means at said points in line with the first 10 named means and extending from said girders towards the sides of the ship for constituting at each of said points with said first named means a continuous transverse girder rigid with the longitudinal girders, said transverse girders providing supports for portions of the hull between the longitudinal 15 girders and the sides of the ship, whereby stresses upon the hull may be resisted by said longitudinal and transverse 20 girders.

7. In a ship's hull, the combination of a skeleton and a skin to cover same, the skeleton comprising a plurality of interior
